UNITED STATES PATENT OFFICE.

HARRY C. GOODRICH, OF CHICAGO, ILLINOIS.

THREAD CUTTER AND HOLDER FOR SEWING-MACHINES.

SPECIFICATION forming part of Letters Patent No. 268,012, dated November 28, 1882.

Application filed June 19, 1882. (No model.)

To all whom it may concern:

Be it known that I, HARRY C. GOODRICH, residing at Chicago, in the county of Cook and State of Illinois, and a citizen of the United States, have invented a new and useful Improvement in Thread Cutters and Holders for Sewing-Machines, of which the following is a full description, reference being had to the accompanying drawings, in which—

- 10 Figure 1 is a perspective showing the lower ends of a needle and presser-foot bar with the thread-cutter attached to the presser-foot bar; Figs. 2 and 3, side elevations, showing opposite sides of the thread-cutter; Fig. 4, a perspective view; Fig. 5, an enlarged top or plan view; Fig. 6, an enlarged side elevation, and Fig. 7 an enlarged side and edge view of the plate forming the combined cutter and spring. The object of this invention is to construct 20 a combined thread cutter and holder for use on sewing-machines, by means of which the thread can be severed and the end caught and held, so as to prevent the unthreading of the needle after the thread has been severed; and 25 its nature consists in providing a frame or support made of a single piece of wire or other suitable material bent to form a shank for attachment to the presser-foot bar or otherwise, an arm for the attachment of the cutting-plate, 30 and an arm or guard for the cutter, and combining therewith a cutting-plate formed from a piece of steel or other suitable material having a lip or prong and a body or main portion, all as hereinafter more specifically described.

35 In the drawings, A represents the cutting and holding plate, which may be made of a piece of thin steel or other suitable material cut or otherwise formed to have a portion, a, which forms the holder, a lip or prong, a', between the edge of which and the edge of a the thread is severed, and a portion, a'', by means of which the attachment is made to the frame or support. The portion a'' is left straight, 40 while the portion a is bent or curved, so that when the device is attached to the presser-foot bar this portion will stand away from such bar, and the lip or prong a' has its extreme end bent in the reverse direction from a, so as

to leave an opening at that point for the ready 50 admission of the thread.

B is the frame or support, made of a piece of wire or other suitable material which can be bent or otherwise formed so as to have a guard or outer portion, b, which is of a bent 55 or curved form, as shown, a body or inner portion, b', between which and b is a space in which is secured the end or portion a'' of the plate A, and a shank or attaching portion, b'', by means of which the attachment is made to 60 the presser-foot bar or other joint.

C is the presser-foot bar, D the presser-foot, E the needle-bar, F the needle, G the throat-plate, and H the bed-plate, of the machine. These parts C, D, E, F, G, and H may be of any 65 of the usual and well-known forms of construction and arrangement, except that the presser-foot bar, as shown, is provided with a transverse opening for the passage of the shank b'' in attaching the thread holder and cutter in 70 position, a set-screw, e, being provided, passing through the presser-foot bar and engaging the shank to render the attachment secure.

The end a'' of the combined cutter and holder A is inserted between the parts b b' of the 75 support B and secured in position by brazing, soldering, or in some other suitable manner, and when in place the portion a comes in contact or bears against the face of b', and is yielding to permit the thread to pass between a and b' above the cutting-point, and at the same time has a spring-pressure which will 80 clamp the thread with sufficient force to prevent the end from escaping after the cutter has performed its work.

85 The operation is as follows: After the sewing is completed the thread is loosened, as usual, and brought around and forced down between a and b' until the edge of the cutter acts and severs it, allowing the work to be removed, 90 and the end of the thread will be caught between a and b' and held, preventing the unthreading of the needle on the return of the needle.

I am aware that various forms of thread 95 holders and cutters have heretofore been constructed for use on sewing-machines, and therefore I do not wish to be understood as broadly

claiming such a device, my invention consisting in the novel construction hereinbefore specifically described, and which I will set forth in the claim.

5 What I claim as new, and desire to secure by Letters Patent, is—

The thread holder and cutter consisting of the plate A, having the holding portion *a* and

the lip or prong *a'*, and frame or support B, having the portions *b b'* and the shank *b''*, substantially as and for the purposes specified.

HARRY C. GOODRICH.
